AIR HEATING APPARATUS

Burton E. Shaw, Southwick, and Richard E. Nest, West Springfield, Mass., assignors to Gilbert & Barker Manufacturing Company, West Springfield, Mass., a corporation of Massachusetts

Application July 21, 1934, Serial No. 736,290

4 Claims. (Cl. 126—99)

This invention relates to improvements in air heating apparatus.

The invention is capable of use in air heating apparatus of various forms. It can, for example, be used to advantage in connection with a warm air furnace, especially in one of the type which is fired with oil or gaseous fuel and has, in addition to the primary radiator which is associated with the combustion chamber, a secondary radiator affording a circuitous path of travel for the gases from the primary radiator. Or it can be used as a separate unit attached to any form of heater, serving as a booster or economizer to utilize the heat from the gases discharged from the main heater for raising the temperature of the air discharged from the heater (in case the heater is a warm air furnace) or for heating a separate supply of air. The invention is capable of use in any heating apparatus in which it is desired to effect a heat exchange between a conductor of hot gases and an upwardly flowing stream of air.

The invention is directed to and has for one object the provision of a conductor for the hot gases of novel shape and construction, characterized in that it enables improved efficiency in the heat transfer between it and the upwardly flowing air stream.

The invention also has for an object the provision of baffles which cooperate with the aforesaid conductor and force the air into close contact with the walls thereof, and promote smooth stream-line flow of the air without eddies at critical points, whereby more air can be forced through the apparatus in a given time by a fan, using a given amount of power, than can be forced through the various prior art apparatus with which we are familiar.

The invention also has for another object the use of baffles, for the above named purpose, which are of trough-like formation capable of containing water for use in humidifying the heated air.

The invention also has for an object the provision of a warm air furnace of generally improved construction, having in particular a novel form of secondary radiator and having also a damper to control direct communication between the primary radiator and the stack, such damper opening and closing automatically accordingly as the pressure within the radiator units is greater or less than a predetermined pressure.

These and other objects will more particularly appear as the detailed description proceeds and will be pointed out in the appended claims.

The invention will be disclosed with reference to the accompanying drawings, in which:

Fig. 1 is a front elevational view of a furnace embodying the invention;

Fig. 2 is a sectional elevational view thereof;

Fig. 3 is a sectional plan view taken on the line 3—3 of Fig. 1;

Fig. 4 is a cross sectional view taken on the line 4—4 of Fig. 1;

Fig. 5 is a sectional plan view taken on the line 5—5 of Fig. 1; and

Fig. 6 is a fragmentary cross sectional view taken on the line 6—6 of Fig. 1.

Referring to these drawings, in which the invention has been shown as embodied in a warm air furnace, a casing 10 of any suitable form is provided. As herein shown, the casing includes a framework composed of a base 11, upstanding columns 12 and horizontally disposed rails 13 which interconnect the columns. The rails 13 support a top wall 14 which is provided with an appropriate number of outlets 15 for the warm air. The spaces between the columns 12, rails 13 and base 11 are enclosed by outer side wall sections 16 suitably secured thereto. Inner wall sections 17 are suitably supported from the members 11, 12 and 13 and provide, with the outer side wall sections, air spaces 18 for insulation purposes. Inlets 19 for cold air are provided on opposite sides of the casing near one lower end thereof. The casing described affords a rectangular enclosure in which all parts of the apparatus are housed.

The cold air inlets 19 open into a chamber 20 (Fig. 2), formed by horizontal and vertical partitions 21 and 22, respectively, which extend transversely across the casing from one inner wall 17 to the other (Fig. 6), and are suitably secured thereto. Underlying and paralleling partition 21 is a wall 23 (Fig. 2) of less width, which extends transversely from one inner side wall 17 to the other and extends longitudinally from the vertical partition 22 toward the adjacent inner end wall 17. The wall 23 terminates short of the adjacent end wall 17 and is connected to an upwardly extending wall 24 having a saw-toothed upper edge 25 (Fig. 6). The wall 23 is provided with an opening leading into a fan chamber 26, formed between partition 22 and a U-shaped member 27, which extends from wall 23 to the floor. The vertical wall 24 and partition 22 carry angle irons 28 from which a series of rectangular-shaped filter elements 29 are supported in zigzag fashion. These filter elements close the space between partition 22 and the saw toothed part 25 of wall 24. Within the chamber 26 is a blower 30, having inlets 30' (Fig. 2) in its side walls, 55

such walls being spaced from the partition 27 (Fig. 6). The outlet 31 of the blower extends through the partition 22 near the lower edge thereof (Fig. 2). The drive shaft 32 of the blower extends through one wall of partition 27 and is driven by a belt 33 and suitable pulleys from an electric motor 34 housed within chamber 20. It will be clear that air is drawn in by the blower through the inlets 19 into chamber 20 and, following the course of the arrows shown in Fig. 2, passes upwardly over the filters 29, thence downwardly through these filters into chamber 26, and thence into the inlets 30' of the blower, being expelled through outlet 31 into the remaining and L-shaped portion of the enclosure within the casing 10.

Within the vertical part of such L-shaped portion is an upstanding cylindrical shell 35, having in its lower portion a fire pot or combustion chamber 36 and having its upper end closed except for a central outlet for the gases. Above the fire pot 36, the shell 35 is provided exteriorly with a circular series of radiating fins 37, encompassed by a cylindrical jacket 38 (Fig. 5). A horizontal partition 39 (Fig. 4) extends transversely across the casing from one inner side wall 17 to the other and longitudinally from the vertical partition 22 to the left hand inner end wall 17 (Fig. 2). This partition 39 has an opening there-through equal in diameter to the internal diameter of the jacket 38. Air from the blower is received in the space below partition 39 and encompasses the lower and fire pot section of shell 35. The air rises through the last named opening and passes upwardly between the shell 35 and jacket 38 through the spaces between the fins 37, as indicated by the arrows in Fig. 2, and is heated in its passage by the primary radiator, composed of the shell 35 and its fins. The air then passes to a secondary radiator to be later described. This shell and its associated parts form the equivalent of a furnace and, in some cases, the invention may be practiced with a furnace of ordinary form which is a separate unit not housed in the same casing with the secondary radiator.

The furnace unit may be fired in any suitable way although gas or liquid fuel is usually employed. As herein shown (Fig. 4), an oil burner of the gun type, designated 40, is employed as indicated in Figs. 1 and 4. The shell 35 has a side opening near its lower end in which is mounted a frame 41 having an opening to receive the nozzle end of the burner. A plate 42, extending vertically from the partition 39 to the floor (Fig. 5) and longitudinally from partition 22 to the left hand inner end wall 17 (Fig. 5) divides off the space below partition 39 and provides a compartment 43 for the burner. Access to such compartment may be had by way of a removable panel or door 44 in the adjacent outer side wall section 16.

The secondary radiator, with which this invention is more particularly concerned, comprises a plurality of substantially horizontally disposed pipes interconnected by headers, through which the gases of combustion flow in their course of travel to the stack and around the exterior of which the air flows and is heated and, if desired, humidified as well. This secondary radiator might be employed as an adjunct to the usual warm air furnace, functioning as an economizer or booster, receiving the gases discharged from the furnace and heating air supplied from any suitable source or superheating the air heated by the furnace, if desired.

This secondary radiator (best shown in Figs. 2, 4, 5 and 6) is housed in the upper part of casing 10 and comprises a centrally and longitudinally disposed cylindrical pipe 46 and two similar but somewhat smaller parallel pipes 47, disposed one on each side of the central pipe. The open ends of these three pipes are connected at one end to a header 48 in the form of a substantially rectangular box of sheet metal, and at the other end to a similar header 49. The central pipe 46, at a point close to header 49, has a short depending pipe 50, which is connected to the outlet in the top wall of the furnace unit 35. A U-shaped strap 51 serves to clamp the pipe section 50 against the top wall of the furnace and such wall serves to support one end of the secondary radiator unit. The other end of such unit is supported by a cross bar 52 (Fig. 6) which underlies the header 48 and is in turn supported at its ends by hangers 53 from the side rails 13.

Mounted in pipe 46 is a deflector 54 (Fig. 2), having a lower and damper section 55 which is hinged at 56 thereto, as will be clear from Figs. 2 and 4. The central part of header 49 has a depression 49' in its lower wall of such form as to allow the damper 55 to swing freely to the left as viewed in Fig. 2. The weight of the damper normally holds it in the position shown.

The header 48 has a deflector 57, mounted centrally therein (Fig. 5) to assist in dividing the gases, which flow to the right in pipe 46, into two streams which pass one to each of the pipes 47. The headers 48 and 49 each have at each end a curved deflector 58 to assist in turning the flow of gases from the header 48 into the pipes 47 or from the pipes 47 into the header 49, as the case may be. The deflectors 58 in header 49 direct the gases inwardly toward the central outlet pipe 59 which is connected at one end to the header and passes through the inner and outer side walls 16 and 17, respectively, and is adapted for connection to the stack. The gases from the furnace unit rise through pipe 50 into pipe 46 and normally pass to the right and travel through a circuitous path, which includes the header 48, pipes 47 and header 49, in order to reach the outlet pipe 59. However, on starting up the burner, the initial puff will open damper 55 and allow the gases to pass directly into the outlet pipe 59 and accelerate the draft. It may function at other times, if and when necessary, to relieve pressure.

The pipes 46 and 47 may each have mounted loosely therein metal pieces 61 of zigzag formation to retard the flow of gases therethrough. Hand holes, covered by removable plates 62 are provided in each header to enable these pieces to be inserted or removed and to allow access to the interior of the headers and pipes for cleaning or other purposes. The combined area of the two pipes 47 is substantially greater than the area of pipe 46, thereby effecting a reduction of velocity of the gases in pipes 47 and affording greater time for these cooler gases to liberate their heat to the air.

Each of the pipes 46 and 47 has secured thereto two sheet metal side pieces 64 arranged in upwardly converging relation and intersecting in a ridge located in the vertical plane which passes through the axis of the pipe. These pairs of plates form stream line shields for their respective pipes. The space between each such pair of pieces 64 and their pipe 46 or 47, as the case may be, is closed off by end plates 65 (Fig. 2) thus forming a dead air space 66. Cooperating with these plates 64, which form a sort of roof of inverted 75

V-form for their pipes, are baffles 67 which are each mounted in spaced parallel relation with the adjacent plate. As shown, each pair of baffles 67 is connected by a deflector wall 68. No baffles, 5 such as 67, are shown cooperating with the two outer plates 64 because they have not been found necessary but, obviously, baffles might be used at such locations if found desirable.

Each pair of members 67 and their connecting member 68 form a unit of trough-like cross section and these units may, in fact, be used as troughs to contain water where humidification of the air is, as here, a desirable feature. In this event, the open ends of the two trough units are 15 connected by two transversely disposed pans 69, one overlying each header, and supported therefrom by plates 70. Water may be supplied to the pans and troughs in any of the ways well known to those skilled in the art.

20 An important feature of the invention resides in the shape and construction of the pipes 46 and 47 of the secondary radiator. Considering these conductors of hot gases as they appear in cross section in Fig. 6, it will be seen that each is essentially a round pipe surmounted by a stream line shield comprising the upwardly converging walls 64. A round pipe is a standard article of commerce, easily and inexpensively manufactured, and lends itself readily to the use of the gas-flow retarders 61 of zigzag formation. The shield is simply a sheet of metal bent into inverted V-shape and superposed on the round pipe and preferably welded thereto, or otherwise secured, so as to insure a joint of good heat conductivity between it and the pipe. The ends of this shield are preferably, although not necessarily, closed off as shown by the walls 65. While the pipe, in its gas conducting portion, might have the same cross sectional shape interiorly as well as exteriorly, according to some features of the invention, the described arrangement is preferred.

25 With a round pipe crossing an upwardly flowing air stream at right angles, the air impinges on the lower periphery of the pipe and splits into two streams which ascend one on each side of the pipe. But these streams do not make effective contact with the upper peripheral portion of the pipe which is naturally the hottest portion. The two streams, flowing upwardly on opposite 50 sides of the pipe, tend to create a vacuum above the pipe and eddy currents are created there, which present a substantial resistance to air flow and materially interfere with an efficient transfer of heat from the hot upper portion of the pipe to the air streams. It is as if the air immediately above the pipe was pocketed there in an area somewhat like that of the space 66. Air streams pass on each side of this area, in which the eddies exist, but they are insulated from the upper portion of the pipe by the pocketed air in the area aforesaid. The shield, however, fills in this area in which the eddy currents exist, and forms a good heat conducting substitute for the pocketed air. Smooth, stream-line flow of air, without eddies is secured and good contact between the walls 64 and the upwardly moving air is secured. The heat from the arc-like top part of the pipe which extends between the lower edges of the shield, is carried off by conduction, some to the 55 lower part of the pipe and some to the walls 64 of the shield. These walls 64 conduct heat from the top wall of the pipe to locations where an effective transfer of the heat to the air can be made. Thus, in a broad sense, the invention puts 70 in the place of an area occupied by air, either

pocketed or moving in eddies, and in any event of poor heat conductivity, a shield of good heat conductivity. The air, occupying the said area, heretofore blanketed off the upper portion of the pipe from the upwardly moving air streams and prevented an efficient heat transfer. With this invention, not only are the eddy currents eliminated at the said area, but a good conductor of heat is placed there where it can come into close contact with the upwardly moving air streams. 10 The baffles 67 are, of course, very desirable in that they force the air streams into close contact with walls 64 and promote smooth, stream flow but, while desirable, they are nevertheless not indispensable. So also the use of these baffles as 15 water troughs is an important and desirable but, nevertheless, not indispensable feature of the invention.

Actual tests made with the same apparatus with and without the shield 64, show that more 20 air can be forced through the apparatus in a given time with the same power applied to fan 30, when the shield is used. These tests also show that the stack temperature is lower when the shield is used, thus indicating that more of the 25 heat has been extracted from the gases and that a more effective heat transfer is effected. That more air can be forced through the apparatus when the shield is used, without the use of more power, is due to the elimination of the eddy currents described and the resistance which they present to air flow. Thus, a greater volume of air can be delivered with the same amount of power and this greater volume heated with the same burner because more of the heat from the burner 35 is utilized when the shield 64 is used.

What we claim is:

1. In an air heating apparatus, a casing having near the lower part thereof an inlet for the air to be heated and near the upper part thereof an outlet for the heated air; a fan for causing 40 air to flow into the inlet, upwardly in the casing and outwardly through said outlet; a radiator unit located within said casing and including a pipe for conducting hot gases and extending substantially horizontally across the path of the upwardly flowing air, said pipe having exteriorly an upper portion in the cross sectional form of an inverted V and a lower portion in the cross sectional form of an arc connecting the free ends 45 of the inverted V-shaped portion, and a baffle on each side of said upper portion to direct the upwardly flowing air after it has been divided by the lower portion of the pipe into smoothly flowing streams along the upwardly converging walls 50 of said upper portion. 55

2. In an air heating apparatus, a casing having near the lower part thereof an inlet for the air to be heated and near the upper part thereof an outlet for the heated air; a fan for causing 60 air to flow into the inlet, upwardly in the casing and outwardly through said outlet; a radiator unit located within said casing and including a pipe for conducting hot gases and extending substantially horizontally across the path of the upwardly flowing air, a shield of inverted 65 V form surmounting the upper part of the pipe, and a baffle on each side of said shield to direct the upwardly flowing air after having been divided by the lower portion of said pipe into two smoothly flowing streams along the upwardly 70 converging walls of said shield.

3. In an air heating apparatus, a casing having near the lower part thereof an inlet for the air to be heated and near the upper part thereof 75

an outlet for the heated air; a fan for causing air to flow into the inlet, upwardly in the casing and outwardly through said outlet; a radiator unit located within said casing and including a 5 pipe for conducting hot gases and extending substantially horizontally across the path of the upwardly flowing air, a shield of inverted V form surmounting the upper part of the pipe and having closed ends to form within the shield and 10 between it and the upper part of said pipe a dead air space, and a baffle on each side of said shield to direct the upwardly flowing air after having been divided by the lower portion of said pipe into two smoothly flowing streams along 15 the upwardly converging walls of said shield.

4. In an air heating apparatus, a casing having near the lower part thereof an inlet for the air to be heated and near the upper part thereof an outlet for the heated air; a fan for causing air to flow into the inlet, upwardly in the casing and outwardly through said outlet; a ra- 20

diator unit located within said casing and including a pair of substantially parallel pipes for conducting hot gases and extending substantially horizontally across the path of the upwardly flowing air, each of said pipes having exteriorly an upper portion composed of upwardly converging walls and a lower portion connecting the free ends of said walls, the adjacent upper portions of said pipes presenting a pair of upwardly diverging walls, and a baffle interposed between 10 said upwardly diverging walls and having upwardly extending portions one adjacent but spaced from each of the last-named walls forming therewith a slot for the stream line flow of air along its wall and a connecting portion to block off 15 the flow of air except through said slots and form with the upwardly extending portions a trough for containing water to humidify the heated air. 5
